Franklin Jr. Attorney

UNITED STATES PATENT OFFICE.

HARRY F. HANKS, OF MYSTIC, CONNECTICUT.

TIMER.

Application filed June 12, 1924. Serial No. 719,576.

To all whom it may concern:

Be it known that I, HARRY F. HANKS, a citizen of the United States, residing at Mystic, in the county of New London and State of Connecticut, have invented certain new and useful Improvements in Timers; and I do hereby declare the following to be a full, clear, and exact description of the invention, such as will enable others skilled in the art to which it appertains to make and use the same.

The object of this invention is the provision of a timer for controlling the ignition system of internal combustion engines such as generally constructed for driving motor vehicles, and the specific purpose of the present invention is to improve the timer generally provided for the Ford engine, whereby to obviate the necessity of lubricating the contacts and which prevents pitting and wear and insures a firm and positive contact and avoids the necessity of frequent replacement.

Other objects and advantages will be apparent and suggest themselves as the nature of the invention is understood.

While the drawing illustrates an embodiment of the invention it is to be understood that in adapting the same to meet different conditions and requirements, various changes in the form, proportion and minor details of construction may be resorted to without departing from the spirit of the invention.

Referring to the accompanying drawing forming a part of the application:

Figure 1 is an elevational view of a timer as seen from the inner end;

Figure 2 is a sectional view on the line 2—2 of Figure 1;

Figure 3 is a sectional detail of a brush contact and holder;

Figure 4 is a detail view of the rotary contact;

Figure 5 is an end view of a brush holder;

Figure 6 is a detail view of the brush carrier; and

Figure 7 is a detail view of one of the brush contacts.

Corresponding and like parts are referred to in the following description and designated in the several views of the drawing by like reference characters.

The numeral 10 denotes the usual timer shell or casing of a Ford engine which is provided upon its inner side with the ordinary fiber ring 11 and brush contacts which constitute the gist of the present invention and which replace the usual segment contacts.

The rotary contact is mounted upon the timer shaft 12 to rotate therewith, and comprises a metal sleeve 13, a disk 14 of suitable insulating material mounted upon the sleeve 13 and a contact 15 secured in an opening formed in the disk 14 and connecting at its inner end with the sleeve 13 and having its outer end flush with the periphery of the disk so as to co-act with the casing contacts.

Each of the brush casing contacts comprises a holder 16 provided with a stem 17 and a lateral extension 18, the stem 17 serving as means for connecting the holder to the casing 10 in the usual way. A recess 18 is formed in the outer face of the holder 16 and receives the brush carrier which comprises a ring 19 and a shank 20, the latter being pivoted at one end to the lateral extension 18 by means of a pin 21. Said brush carrier is cut away as at 20^a to provide clearance for its pivotal movement. The brush contact 22, preferably of carbon, fits snugly within the ring 19 and has an outer flange 23 at its inner end to prevent outward displacement of the contacts. A helical spring 24 normally exerts an outward pressure upon the brush contact 22 and the free end 19 of the brush carrier to urge the same outwardly to the position of Figure 3 whereby to hold the contacts in engagement with the roller 14. While it is preferred to have the brush contact 22 of carbon, nevertheless it may consist of copper or other suitable material. A timer constructed in accordance with the present invention obviates the necessity for lubricating the contacts and prevents irregular wear, obviates pitting and permits of ready replacement of the brushes and insures positive contact and a smooth running engine.

What is claimed is:—

1. In a timer of the character specified, a casing contact comprising a brush holder having a lateral extension and provided in its outer side with a recess and an opening, a brush carrier disposed within said recess and pivoted at one end to the lateral extension of the holder, a brush at the opposite end of the carrier having a lateral retaining flange, and a spring in line with said

110

brush and within the opening of the holder and normally exerting an outward pressure upon the free end of the carrier.

2. In a timer of the character specified, a casing contact comprising a brush holder provided with a recess and an opening, a brush carrier disposed with said recess and pivoted to the holder, a brush borne by the carrier having a lateral retaining flange 10 engaging the carrier, and a spring in line with said brush located within the opening of the holder and normally exerting an outward pressure upon the free end of the carrier.
- 15 3. A casing contact for a timer of the character specified, the same comprising a holder

having a stem and a lateral extension, and having a recess and an opening in its outer side, a brush carrier comprising a ring and a shank and disposed within the recess of 20 the holder and pivoted at one end to the lateral extension thereof, a brush fitted within the ring of the carrier and having an outer flange at its inner end, said ring and holder having communicating recesses to accommodate movement of said flange, and a helical spring within the opening of the holder in line with and exerting an outward pressure upon the brush and carrier. 25

In testimony whereof I affix my signature.

HARRY F. HANKS.
